WASTE CONTAINER OR SIMILAR ARTICLE

John T. Osborne, 1431 Amsterdam Road,
Covington, Ky. 41011

Filed Mar. 17, 1966, Ser. No. 1,521

Term of patent 14 years

(Cl. D58—17)

Fig. 1

Fig. 4

Fig. 2

Fig. 3

FIGURE 1 is a top plan view of a waste container or similar article embodying my new design;

FIGURE 2 is a side elevational view, the side opposite that shown being the same in appearance except for the absence of the handle on the cover;

I claim:

The ornamental design for a waste container or similar article, as shown and described.
